UNITED STATES PATENT OFFICE

GEORGE L. ERNST, OF PORT HURON, MICHIGAN, ASSIGNOR TO THE DAVID-
SON-MARTIN MANUFACTURING COMPANY, OF SAME PLACE.

PURIFIER, SEPARATOR, AND GRADER.

SPECIFICATION forming part of Letters Patent No. 658,837, dated October 2, 1900.

Application filed October 16, 1899. Serial No. 733,726. (No model.)

To all whom it may concern:

Be it known that I, GEORGE L. ERNST, a citizen of the United States, residing at Port Huron, county of St. Clair, State of Michigan, have invented a certain new and useful Improvement in Purifiers, Separators, and Graders; and I declare the following to be a full, clear, and exact description of the invention, such as will enable others skilled in the art to which it appertains to make and use the same, reference being had to the accompanying drawings, which form a part of this specification.

This invention has for its object certain new and useful improvements in a purifier, separator, and grader adapted for a variety of uses, the same being more particularly designed for purifying and grading flour and like products, the present invention having reference to certain improvements upon devices of this character for which United States Letters Patent were granted June 12, 1894, No. 521,402, and No. 543,927, granted August 6, 1895.

To this end the invention consists of the structure, combination, and arrangement of devices and appliances hereinafter described and claimed, and illustrated in the accompanying drawings, in which—

Figure 1 is a view in vertical section illustrating the invention. Fig. 2 is a vertical transverse section on the line 2 2, Fig. 1. Fig. 3 is a horizontal section on the line 3 3, Fig. 1. Fig. 4 is a vertical section on the line 4 4, Fig. 1.

This invention aims to secure in a device of this character greater utility and efficiency and to effect a more thorough and satisfactory grading of the stock fed to the machine and to combine in one machine novel features and means whereby more effectual separation and grading of the stock may be secured.

As illustrated in the drawings, an inclosing case is provided, (represented at *a*), the interior of which is divided by a partition *b*, preferably made rounding or arc-shaped, thereby forming within the interior of the case a main air-chamber *c* and a transverse air-trunk or passage therebelow, (indicated at *d*.) A fan-case *e*, with its fan, is located in the

upper end of the case communicating at one side with the main chamber *c* and at the opposite side with a vertical air-trunk *f*, opening into the transverse trunk or passage *d*. 55 These features may be constructed in the main as disclosed in the Patent No. 543,927, above mentioned, and the chamber *c* and the air-passage *d* may be arranged and supplied with the various provisions enumerated in 60 said last-named patent.

Within the main air-chamber *c* are located a series of cant-boards *g*, arranged in pairs converging toward their lower edges and discharging into discharge-ducts, (indicated at *h*.) 65 Above the adjacent cant-boards *g* *g* projects a wall *i*.

The cant-boards *g* tend to create, obviously, dead-air chambers above the discharge-ducts *h* *h*, (indicated at *k* *k*.) the stock falling into 70 said dead-air chambers *k* being little or not at all affected by the air circulation permitting a separation of the stock, the separations of the stock falling into the discharge-duct *h*, as described in said patents. In these dead-air chambers *k* *k* the heavier portions of the stock thereabove will naturally separate and drop to the base of said air-chambers to be discharged therefrom. So, also, as embodied in the Patent No. 543,927, above mentioned, 75 the transverse air-trunk *d* is provided with cant-boards *l*, diverging at their base, the adjacent sides of the case *a* also converging to form dead-air chambers *m* *m* at the base of the transverse air-trunk, said latter chambers provided with discharge-ducts *n* *n*, 80 whereby additional separations of the stock may take place. The main case *a* may be provided with supporting-legs, (indicated at *p* *p*.) 85

The main case *a*, with its interior structures and arrangements, embodied in the patent last-mentioned, is provided in my present invention with an auxiliary chamber (indicated at *q*) at one side the main chamber *c*, 95 and in which auxiliary chamber are located air-passages 1, 2, and 3, communicating at their base with the air-trunk *d*, and at the top thereof through the upper end of the auxiliary chamber with the main air-chamber, as 100 through an opening *j*. The auxiliary chamber *q* may be constructed with a suitable case

or shaker, (indicated at *r*.) In the auxiliary chamber *q* are also located a series of screens and discharge-duets for securing a more effectual grading of the stock. Thus a series 5 of screens are indicated at *t u v*, which may be arranged in any suitable manner within the chamber *q*. To this end they may be secured, for example, to the case *r*. Below each of said screens is a corresponding cant 10 or return board (indicated at *w x y*) reaching from the rear end of the adjacent screen in the opposite direction. The boards are arranged at an angle to the screens, and the boards *w x* discharge, respectively, upon the screens *u v*. Below the discharge ends of said screens, respectively, are located a corresponding series of separating or deposit chambers, (indicated at 4, 5, and 6,) provided with corresponding discharge-duets 7, 8, and 9.

20 The air-passage 1 may be formed by a vertical deflecting-partition (indicated at *z*), and the adjacent end of the separating-chamber 4. The outer walls of each of the deposit-chambers 4, 5, and 6, respectively, are formed by 25 deflecting-partitions 10, 11, and 12, projecting upwardly at an angle and offset at the upper portion thereof and arranged to project over the corresponding deposit-chambers, respectively. The vertical partition *z* is also 30 preferably constructed with an upwardly-inclined (wall indicated at 13) to deflect the air-current passing through the air-passage 1 against the wall 10. So, also, the current passing upward through the air-passage 2 is 35 deflected in consequence of offsetting the wall 10, as above described, while the air passing through the passage 3 is also offset in consequence of the offsetting of the wall 11. The deposit-chamber 4 opens upward 40 under the discharge end of the screen *t*. The deposit-chamber 5 opens upward underneath the discharge end of the screen *u*, while the deposit-chamber 6 opens upward under the discharge end of the screen *v*. The slanting 45 return-boards *w x y* all tend to throw inward the air passing upward through the passages 1 2 3, so that the various air-currents through said passages 1 2 3 converge and commingle beneath the discharge end of the screen *t* and 50 pass through the opening *j* into the main air-chamber *c*.

In the present case I prefer to locate the feeding-hopper 14 intermediate the sides of the case of the machine and to locate therebeneath a screen 15, discharging at its outer end outside the machine, the stock passing therethrough falling upon a cant-board 16, which discharges upon the screen *t*. Beneath the screen 15 is a separating-board 17, the 55 same being preferably a continuation of the cant-board 16, cutting off the air from beneath said screen.

The operation of the device so far explained is as follows: It is evident that the fan located 60 in the upper part of the inclosing case produces an ascending suction-current through the air-passages in the auxiliary chamber and

a blast-current upon the other side of the fan, the ascending suction-current and blast-current forming an endless air-current. The deflecting-partitions in the auxiliary chamber, as above described, form independent passages for the ascending current, each of said air-passages being provided with an adjacent deposit-chamber for the deflected and precipitated material. As shown in the drawings, also, said partitions increase gradually in height in a line having a general direction toward the opening *j* or in a general direction toward the fan. The shaker *r* carries a series 70 of alternating successive screens and return-boards one below another, each successive screen receiving the product passing through the screen above, and said screens each arranged with its discharge end corresponding 75 with the increased height of the partitions, so as to tail over the coarser product into its own separate air-passage of said series, a settling-chamber being thus located between the said screen and air-passages, and the fan 80 adapted to receive the material precipitated by gravity from the suction-current. The stock fed into the hopper 14 is discharged upon the screen 15, the stock passing therethrough discharging upon the boards 16 and 17, whereby the stock is discharged upon the screen *t*. The stock discharged from the inner edge of the screen *t* is discharged therefrom in such a manner that the ascending air-current thereat strikes it from below to 90 separate the lighter products and carry them into the chamber *c*. The portion of the stock discharged from the screen *t* too heavy to be carried by the air-current into the chamber *c*, it 95 will be perceived, drops into the deposit-chamber 4, from whence it may be discharged through the duct 7. The slanting wall or partition 13 is offset, so that its inner surface overhangs the inner wall of the chamber 4, leaving an air-passage between the upper edge of said inner wall and the board 13, as above described. The stock passing through the screen *t* is discharged upon the return-board *w* and 100 thence upon the screen *u*. That portion of the stock which is discharged from the inner edge of the screen *u*, it will be seen, falls upon the ascending current of air passing through the passage 2, whereby another separation takes place, the lighter portions of the stock 105 being carried upward by the air-current and the remainder dropping into the deposit-chamber 5, the wall 10 being offset, so as to overhang the upper edge of the inner wall of said chamber 5, as shown. The stock passing through the screen *u* falls upon the return-board *x*, passing thence up on the screen *v*. That portion of the stock discharged from the inner edge of the screen *v* falls upon the ascending air-current passing through the passage 3, whereby another separation takes 110 place, as before, the heavier portions of the stock thereat falling into the deposit-chamber 6. The portion of the stock passing through the screen *v* falls upon the return-board *y* and 115

is discharged into a chamber 18, from whence it may be discharged through a duct 19. The product passing into the chamber 18 will be flour-dust.

5 The case or shaker *r*, with the screens and their respective return-boards, is preferably made agitable in any suitable manner. I do not limit myself to any particular way of agitating the same; but, as shown, the case *r* 10 may have connected therewith an arm (shown in dotted lines at 20) arranged in the path of a rotatable knocker 21. Within the main air-chamber *c* I prefer to locate a diaphragm 22, which may be constructed in any 15 suitable manner and which may be made vertically adjustable, the lower end being shown adjustably engaged with a movable arm 23. This diaphragm is located in the vicinity of the orifice *j* and over the chamber *k* first occurring below said opening. The location of the diaphragm is such as to permit, preferably, a portion of the air to pass thereover, thereby checking the force of the air-current at the base thereof and forming a separation 20 of the stock to be made over the corresponding dead-air chamber *k*. So, also, adjacent to the entrance into the fan-case is another diaphragm, (indicated at 24,) preferably made foraminous and adjustable, as upon a swing- 25 arm 25. This diaphragm obviously checks the air-draft therebeneath, permitting another separation into the corresponding chamber *k*. I do not limit myself to any precise 30 number of these diaphragms and corresponding separating dead-air chambers within the chamber *c*; nor do I limit myself to any specific 35 number of separating or dead-air chambers in the lower portion of the transverse air-duct *d*. I would have it understood, 40 moreover, that I do not limit myself to any given number of screens within the auxiliary chamber *q*, nor to any specific number of air-passages and deposit-chambers within the chamber *q*. It will be evident that the main 45 chamber *c* is in the nature of an expansion chamber. This fact, in connection with the separating devices above explained, will secure corresponding separations within said chamber. It will be obvious that the initial 50 separation is made by the screen 15. The next grading or separation will be made at the discharge end of the screen *t*, as above explained, another at the discharge end of the screen *u*, and another at the discharge 55 end of the screen *v*, these gradings or separations being made in the auxiliary chambers *q*. The stock carried by the current into the chamber *c* is graded into the various chambers *k*, and further separations are made 60 at the base of the transverse duct *d*.

The case *r* is preferably made with three sides. The bumper-arm 20 may be in the nature of a spring-arm. The walls of the deposit-chambers 4, 5, and 6 are so formed 65 as to permit air circulation thereabout, so that the air-current may enter the air-ducks adjacent thereto. To this end the walls of

the chambers may converge laterally, as indicated more particularly in Fig. 2.

The stock discharged from the ducts 7, 8, 70 9, and 19 might be kept separate, if desired, or said ducts might converge after the air has properly acted upon the stock so as to discharge from a single chute.

In Fig. 2 two of the spring-arms 20 are 75 shown, a cross-arm having its extremities resting thereupon, the bumper 21 engaging the cross-arm 26.

What I claim as my invention is—

1. In a purifier, separator and grader, the 80 combination within an inclosing case, of a main air-chamber, an auxiliary air-chamber opening into the main air-chamber toward the upper end thereof, a series of deflecting-partitions forming independent air-passages 85 within the auxiliary chamber, each provided with an adjacent deposit-chamber for the deflected and precipitated material, said partitions gradually increasing in height in a line having a general direction toward the opening 90 of the auxiliary chamber into the main air-chamber, means to effect ascending air-currents through said air-passages into said main air-chamber, and separating devices in said auxiliary chamber arranged to discharge 95 into the ascending air-currents through said air-passages.

2. In a purifier, separator and grader, the combination within an inclosing case, of a fan located in the upper portion of the case, a 100 main air-chamber communicating with the interior of the fan-case on one side thereof, a vertical air-trunk communicating with the opposite side of the fan-case, a transverse air-trunk below the main air-chamber communicating with said vertical air-trunk, an auxiliary chamber at one side of the main air-chamber and opening thereinto, plural deflecting-partitions in said auxiliary chamber forming independent air-passages communicating 105 at their base with said transverse air-trunk, and at their upper ends with said main air-chamber, each of said air-passages provided with an adjacent deposit-chamber, and plural separating devices in said auxiliary 110 chamber arranged to discharge into the air-currents in ascending through said air-passages, said partitions gradually increasing in height in a direction toward the fan, substantially as described. 115

3. In a purifier, separator and grader, the combination within an inclosing case, of a main air-chamber, an air-trunk therebelow, an auxiliary chamber at one side the main air-chamber and opening thereinto, deflecting-partitions forming independent air-passages within the auxiliary chamber communicating at their base with said air-trunk, and at their upper ends through the auxiliary chamber with the main air-chamber, a deposit-chamber adjacent to each of said air-passages, means to effect an air circulation 125 through said air-trunk and upward through said air-passages into the main air-chamber 130

and from said main air-chamber into said air-trunk, and separating devices in said auxiliary chamber arranged to discharge into the air-currents ascending through said air-passages, said partitions gradually increasing in height in a direction toward the opening of said auxiliary chamber into the main air-chamber.

4. In a purifier, separator and grader, the combination within an inclosing case, of a main air-chamber provided with separating devices, an air-trunk therebelow, an auxiliary chamber at one side the main air-chamber and opening thereinto, deflecting-partitions forming independent air-passages within the auxiliary chamber communicating at their base with said air-trunk, and at their upper ends with the main air-chamber, a shaker within the auxiliary chamber carrying a series of alternating screens and return-boards one below another, and means to effect an air circulation through said air-trunk and through said air-passages into said main air-chamber, each of said screens arranged to discharge the stock passing thereover into the air-current ascending through the corresponding air-passage.

5. In a purifier, separator and grader, the combination within an inclosing case, of a main air-chamber, a transverse air-trunk therebelow, a vertical air-trunk on one side the main air-chamber communicating at its base with a transverse air-trunk, a fan and its case located in the upper part of the inclosing case communicating on opposite sides thereof with the main air-chamber and with the upper end of the vertical air-trunk, an auxiliary chamber on the side of the main air-chamber opposite the vertical air-trunk communicating at the top thereof with the main air-chamber, a feeding device discharging into the upper end of the auxiliary chamber, deflecting-partitions forming independent air-passages within the auxiliary chamber communicating at their upper ends through the auxiliary chamber with the main air-

chamber, and at their lower ends with said transverse air-duct, deposit-chambers located in said auxiliary chamber adjacent to the corresponding air-passages, and separating devices arranged one below another in the auxiliary chamber to discharge the stock passing thereover into the air-currents passing through said air-passages, said partitions arranged to deflect the air-currents rising through said air-passages over corresponding deposit-chambers, respectively.

6. In a purifier, separator and grader, the combination within an inclosing case, of a main air-chamber, a fan located in the upper part of said inclosing case arranged to produce an ascending suction-current upon one side through the main air-chamber, and a blast-current upon the other side and forming an endless air-current, an auxiliary chamber opening at its upper end into the main air-chamber, deflecting-partitions forming independent passages within the auxiliary chamber for the ascending current, a deposit-chamber adjacent to each of said air-passages to receive the deflected and precipitated stock, said partitions increasing gradually in height in a line having a general direction toward the fan, a shaker within the auxiliary chamber carrying a series of alternating successive screens and return-boards, one below another, each successive screen receiving the product passing through the screens above, and said screens each arranged with its discharge end corresponding to the increased height of the partitions to tail over the coarser product into its aforesaid independent air-passage, said main air-chamber located between the said screens and the air-passages and the fan, and adapted to receive the stock to precipitate each by gravity from the suction-current.

In testimony whereof I sign this specification in the presence of two witnesses.

GEORGE L. ERNST.
